J. B. MORROW

COAL OIL BURNER

Filed March 10, 1927

Patented Jan. 8, 1929.

1,698,061

UNITED STATES PATENT OFFICE.

JAMES B. MORROW, OF OAKLAND, CALIFORNIA.

COAL-OIL BURNER.

Application filed March 10, 1927. Serial No. 174,166.

My invention relates to improvements in coal oil heaters and it consists in the combinations, constructions, and arrangements hereinafter described and claimed.

5 An object of my invention is to provide a coal oil heater which provides centrally disposed means for moving the wick, whereby uniform pressure is applied at all points around the circular wick for raising or lowering the same, thus preventing binding.

10 A further object of my invention is to provide a device of the type described in which novel means is provided for preventing the top edge of the wick from burning. This 15 construction prevents part of the edge of the wick from burning more rapidly than other parts of the wick, this burning normally being caused by an unevenly cut wick. It will therefore be seen that the wick will burn 20 uniformly over its entire exposed area and will therefore give off a uniform flame.

25 Other objects and advantages will appear in the following specifications, and the novel features of the invention will be particularly pointed out in the appended claims.

30 My invention is illustrated in the accompanying drawing forming a part of this application in which the figure shows a vertical section through the device.

35 In carrying out my invention I provide a chimney 4 which is supported by a casing 3 which in turn is supported by legs 2. The casing 3 has an inwardly extending bead 1 which carries an oil fount 5.

40 I will first describe the means for raising and lowering the wick 6. The oil fount 5 has an air pipe 7 therein, this being centrally disposed and housing the working mechanism hereinafter described. A radially extending tube 8 extends through the oil fount 5 and houses a cylindrical casing 9. The casing 9 is frictionally held in the tube 8. Within the casing 9 I mount a shaft 10 which is journaled in the ends 11 and 12 of the 45 casing 9. The inner end of the shaft 10 carries the pinions 13 while the outer end carries an actuating wheel 14.

50 A perforated rack bar 15 is provided with arms 16 which have trunnions 17 slidably mounted in slots 18. The trunnions 17 extend into a wick carrying cylinder 19 to raise the wick 6 when the wheel 14 is actuated.

55 A burner cap 20 is slidably mounted upon a rod 21 and carries a flange 22 which has a downwardly bent portion 23 partially cov-

ering the upper edge of the wick 6. The portion 23 prevents the upper edge of the wick 6 from burning.

60 A stop nut 24 is secured to the top of the rod 21 for limiting the movement of the burner cap 20. The lower end of the rod 21 is supported by a cross bar 25 which in turn is secured to supporting members 26 that have L-shaped slots 27 therein for removably receiving pins 28 carried by the air pipe 7.

65 From the foregoing description of the various parts of the device, the operation thereof may be readily understood. The chimney 70 4 is hinged to the casing 3 in the usual manner and is adapted to be swung back for permitting the oil fount 5 to be removed when necessary. A slot 29 is provided for permitting the shaft 10 to be moved through 75 the casing 3 when the oil fount 5 is removed. The wheel 14 is disposed at a sufficient distance above the floor for permitting the ready operation of the wheel. It will also be noted that there will be no binding action 80 between the cylinder 19 and the air pipe 7 when the cylinder is moved. This is true because the lifting force is centrally disposed with respect to the cylinder 19. A uniform flame from wick 6 is assured because the portion 23 of the flange 22 will cover any frayed edges of the wick and thus prevent these frayed edges from burning.

85 I claim:

1. In an oil heater, an air pipe, a wick 90 cylinder slideable thereon, a wick mounted on the exterior of the cylinder so as to be substantially flush therewith at the upper end; an axially movable member on the inside of the cylinder terminating at its upper end in 95 forked branches passing through slots in the air pipe into the body of the cylinder so as to allow the latter to be adjusted by the former, and means axially disposed in said air pipe for limiting the upward movement of 100 said cylinder.

2. An oil heater comprising in combination an oil fount, an air pipe extending centrally through said fount, a burner cap slidably mounted in said air pipe and means 105 connected to the burner cap and detachably engaging the air pipe to limit the upward movement of the burner cap said last means comprising a cross-bar attachable to the inside of the air pipe and an adjustable rod 110 extending upward from the cross bar through the burner cap with means on said

rod for limiting the upward movement of the burner cap.

3. An oil heater comprising in combination an oil fount, an air pipe extending centrally through said fount, a burner cap slidably mounted in said air pipe and means connected to the burner cap and detachably engaging the air pipe to limit the upward movement of the burner cap; said limiting means comprising a cross-bar with a support-

ing member having bayonet slots therein, said slots having detachable engaging means on the interior of the air pipe and a threaded rod extending through said cross-bar and through the burner cap, and having a stop device on the top of the rod to limit the upward movement of the burner when elevated by the upward movement of the wick. 15

In testimony whereof I affix my signature.
JAMES B. MORROW.
